UNITED STATES PATENT OFFICE.

SAMUEL OLSON, OF OAK PARK, ILLINOIS, ASSIGNOR TO SAMUEL OLSON & COMPANY, OF CHICAGO, ILLINOIS, A CORPORATION OF ILLINOIS.

SELECTIVE ELECTRIC CONTROL SYSTEM.

Application filed January

2, 1926. Serial No. 79,052.

The purpose of this invention is to provide a simple control for elevators, conveyers and the like by which from a fixed point in the mechanism may be stopped when the load carried thereby reaches a particular station. It consists in certain features and elements in combination as herein shown and described and as indicated by the claims.

In the drawings:

10 Figure 1 is in the nature of a vertical section illustrating a portion of an elevator with this invention applied thereto.

15 Figure 2 is a detail view showing the interior construction of a limit switch used as an element of the control.

Figure 1 shows a portion of an elevator of the general type more fully described in my Patent No. 1,325,857 issued December 23, 1919 in which two pairs of chains are mounted for parallel travel and are provided with transversely disposed flights in the form of angle rails which are adapted to support loads such as trays, extending transversely from one pair of chains to the other. The drawing shows only one pair of the chains 10, of such an elevator, but includes the angular flights, 12, attached thereto. One of the trays is shown in full lines at 3 and in dotted lines at 13, the position of the same tray 20 is indicated as it arrives at the station opening, 14, at which it operates to stop the movement of the elevator so that the tray may be manually removed by an attendant. An elevator of this character is frequently 25 employed in a building such as a hotel for conveying loaded trays to the various floors for delivering meals to guests in their rooms; the openings, 14, may be understood therefore as each representing an access opening 30 in the wall at a different floor level traversed by the elevator.

The power for driving the elevator is supplied by a motor 15, receiving its current through a starting box or rheostat, 16, of any suitable type. In addition to the starting box, 16, I provide a control board, 17, having a swinging switch arm, 18, which may connect at will with any of a number of contacts, preferably marked with the numbers of the respective floors to which they correspond, as, "1, 2, 3, 4," as shown in the drawing. The arrow X, indicates that the normal direction of travel of the elevator is upward. The current supply wires leading from the starting box, 16, comprise a wire,

y, connected to the swinging switch arm, 18, and a second wire, z, extending directly to the motor, 15. From each of the contact points on the board, 17, an individual wire extends to one of the limit switches, A, B, C, D, whose internal construction is indicated in Figure 2. Each switch includes a lever arm, 19, normally extending into the path of upward travel of the trays carried by flights, 12, of the elevator, so that the trays will deflect these levers, 19, as they pass. Except when their levers, 19, are thus deflected, each of the limit switches, A, B, C, D, provides a path for the electric current from the board, 17 to the motor, 15. For example a wire, 20^a, leads from the contact member, 1, on the board into the switch, A, and wire, 21^a, connects with a wire, 21, which extends to the motor, 15.

As illustrated in Figure 1, the device is arranged to automatically stop the tray, 3, when it arrives in position to swing aside the arm, 19, of the limit switch, C, this position being shown in dotted lines at 13. The arm, 18, on the board, 17, is set for contact with the terminal of the wire, 20^c, leading to the switch, C, so that until the tray arrives at the position shown at 13, the circuit for the motor, 15, is completed through the wire, 20^c, limit switch, C, wire, 21^c, and the wire, 21. As the tray reaches this limit of its travel, the arm, 19, is swung to the position shown in dotted lines. The wires, 20^c and 21^c, are connected within the switch box to binding screws, 22 and 23, respectively, from which spring arms, 24 and 25, extend in contact with opposite sides of a conductor pin, 26. Said pin, 26, is carried on the short arm, 27, of the lever, 19, which is fulcrumed at 28, so that when the lever is swung by contact with the tray, 3, the pin, 26, is carried out of contact with the arms, 24 and 25, thus breaking the motor circuit and causing the mechanism to come to rest. Within the casing of switch, C, a spring, 29, is arranged to return the arm, 19, yieldingly to its normal position so as to complete the circuit through the parts, 24, 26 and 25, as soon as the tray, 3, is removed from the elevator, thus automatically causing the chains, 10, and flights, 12, to resume their upward motion.

Since the chains, 10, are endless, it is not necessary to provide for reversing the direction of drive of the motor, 15. When an-

other tray is to be elevated to the same or a different floor, the control switch arm, 18, is merely set into contact with the terminal corresponding to the desired floor or station, 5 and the motor is then started by means of the switch, 16; the limit switch thus included in the circuit is relied upon to stop the mechanism when the tray has reached the chosen station.

10 I claim:—

1. In combination with an endless conveyer and driving means therefor, a plurality of stations associated with the conveyer, a member adjacent each station in position to engage a load on the conveyer, and means at a distance from the stations adjustable to co-operate with such member at any selected station and adapted to stop the conveyer when the load arrives at the selected station 15 20 and engages the said member, said member being adapted to start said conveyer when the load is removed therefrom.

2. In combination with an endless conveyer and means for driving it, a plurality 25 of stations, a member associated with each station in position to engage a load on the conveyer, a control board at a distance from the stations having a plurality of terminals electrically connected respectively with said members at the stations, and also having electrical connection with means controlling the driving means, and a selecting device at the control board through which the said member at any selected station may be connected 30 35 for controlling the drive to stop the conveyer when a load arrives at the selected station, together with means associated with each of said members for automatically starting said conveyer in motion after said load is removed therefrom.

3. In combination with an endless conveyer, an electric motor for driving it, and a plurality of stations associated with the conveyer, the motor circuit including a wire 45 having branches extending through switches adjacent the respective stations and thence to a series of grouped contacts, together with a selector switch co-operating with said grouped contacts for placing any one of the

station switches at will in the motor circuit, 50 each station switch having circuit-breaking means extended normally in the path of a load on the conveyer, whereby the arrival of the load at the selected station opens the motor circuit for stopping the conveyer, said 55 switches including means for closing the motor circuit when said load is removed therefrom.

4. In combination with an elevator, driving means therefor, and a plurality of stations, a member associated with each station in position to engage a load on the elevator, means at a distance from the stations adjustable to co-operate with any selected one of said members and adapted to stop the elevator when the load engages the selected member, said selected member being provided with automatic means for starting said elevator after the load is removed therefrom. 60 65

5. In combination with an elevator comprising parallel endless belts spaced apart and provided with flights projecting toward each other for supporting trays which bridge the space between the belts, a plurality of stations associated therewith, an electric 70 75 motor for driving the belts, the motor circuit including a wire having branches extending through switches at the respective stations, each switch having an arm which projects between the belts for contact with the trays or loads carried thereby, the arm being movable by such contact to open the switch, and said branches extending from the switches to a control board having a contact corresponding to each branch, and a selector member in the motor circuit movable to engage any one of said contacts at will to adapt the switch at a selected station to be opened by the load for stopping the motor 80 85 when the load arrives at said station. 90

6. The combination of an endless conveyer having driving means therefor and means associated therewith engageable by the load carried by the conveyer at predetermined points along the path of travel of the load whereby to stop the conveyer until the load is removed therefrom. 95

SAMUEL OLSON.
